UNITED STATES PATENT OFFICE

HANS WEISSENBOECK, OF LOS ANGELES, CALIFORNIA

LOCK

Application filed February 6, 1929. Serial No. 337,831.

This invention relates to locks, and more especially to combination locks, i. e., to that type of lock which does not require a key for its operation, but which may be operated by manipulating accessible portions of the lock in a predetermined manner.

An object of the invention is the provision of a lock, which, after being properly mounted, accessibly presents an operating handle and a plurality of buttons, each of which buttons is formed by the projecting end of a push rod, and each of which must be depressed a predetermined number of times before the operating handle may be activated to release the lock.

A further object is the provision of a lock of the general character described, having means for retaining the operative parts of the lock in unlocked position after the combination has once been set, so that subsequent depression of any of the buttons will not again set the lock, this means being so arranged that it may be instantly rendered inoperative when it is desired to again set the lock.

A further, and one of the invention's more important objects, is the provision of a combination lock which is of very simple nature, and which contains a relatively few constituent parts, each of which may be very easily and economically manufactured. Furthermore, the lock is very easily assembled, being composed of a minimum number of parts which require threading for their proper mounting in association with the other parts of the lock. This is an important detail in that one of the problems in lock manufacturing, is to eliminate all screwed connections possible, because of the length of time required in making this type of connection.

The invention possesses other objects and advantageous features, some of which, with those enumerated, will be set forth in the following description of the invention's particular embodiment which is illustrated in the drawings accompanying and forming a part of the specification.

Referring to the drawings:

Figure 1 is a front elevation of a lock embodying the features of my invention.

Fig. 2 is a horizontal, medial sectional view,

the plane of section being taken upon the line 2-2 of Fig. 1, with the direction of view as indicated.

Fig. 3 is a vertical, transverse sectional view taken upon the line 3-3 of Fig. 2, with the direction of view as indicated.

Fig. 4 is a vertical, medial sectional view of the lock casing, and showing the shank and retaining sleeve mounted therein in side elevation.

Fig. 5 is a transverse, vertical sectional view taken upon the line 5-5 of Fig. 2, with the direction of view as indicated, and showing the locking rods in locking position.

Fig. 6 is a view similar to Fig. 5, but showing the locking rods moved to releasing position.

Fig. 7 is an enlarged, fragmentary, sectional view of a portion of the sleeve, and showing one of the retaining blocks in side elevation.

Fig. 8 is a view similar to Fig. 7, of a slightly modified form of retaining block.

In terms of broad inclusion, the lock of the present invention comprises a bolt operating member mounted within a casing, and a plurality of locking rods slidably mounted so as to optionally release or hold inoperative, the bolt operating means. Each of the locking rods is adapted to be moved to releasing position in a predetermined number of successive steps, each of these steps being effected by the activation of a push rod, one of which is associated with each of the locking rods. Consequently, the lock can not be unlocked until each of the buttons has been activated the proper number of times, with the result that secret knowledge is required before the lock can be released.

Specifically describing the invention in its most preferred embodiment of which I am at present aware, the operative parts of the lock are mounted within a casing 6, having a flange 7 extending therefrom to facilitate mounting the lock in any desired supporting structure such as a door. A plurality of holes 8 are provided in the flange 7 for the reception of screws or analogous fastening means.

A shank 11 is journaled within the casing for rotary movement, and this shank 11 may

be extended from the casing 6 in any convenient manner as at 12, and provided with threads 13 or other suitable attaching means to facilitate connection of the shank 11 to a latch bolt or any other mechanism which it is desired to have operated by the lock of the present invention. A disc 14 is receivable upon a squared portion 16, so that the disc is in effect, a flange rigid with the shank 11. 5 A convenient method of assembly is afforded by providing a slot 17 in the top of the casing 6 leading into the recess 18 in which the disc 14 is mounted, so that the disc 14 may first be slipped into the recess 18 through 10 the slot 17, and the shank 11 then thrust through the bore 19 of the casing 6, and through the disc 14. A pair of back plates 21 and 22 are adapted to fit into an annular groove 23 in the shank 11, to prevent the shank from being withdrawn from the casing 6; and these plates 21 and 22 are removably securable in place by screws 24 or their 15 equivalent.

The disc 14 or flange, as this member will 20 hereinafter be termed, is provided with a plurality of notches 26 in its periphery; and associated with each notch 26, is a locking rod 27. These rods are mounted for longitudinal sliding movement in the casing 6, with 25 their axes disposed in parallelism with that of the shank 11; and each locking rod 27 passes through one of the notches 26 in the flange 14, as clearly shown upon Figs. 5 and 6. Consequently, the locking rods 27 normally hold the flange 14, and with it the shank 11, against rotary movement. However, each locking rod 27 is provided with 30 a notch 28, and each rod 27 is adapted to be so moved that its notch 28 comes into register with the flange 14, and permits rotation of the shank 11 so as to operate the mechanism to which the shank 11 is connected. A handle 29 is rigid with the shank 11 at the front end of the lock, to facilitate turning the shank 35 after all the locking rods 27 have been moved to releasing position.

As shown upon Fig. 2, the notches 28 in the various locking rods 27, are disposed at different points in respect to the length of the rods 27, with the result that it is necessary to move each of the rods 27 a different distance in order to effect releasing of the lock. Furthermore, each locking rod 27 is provided with a spring 31 under compression between 40 the inner end of the rod 27 and the bottom of the recess 30 in the casing 6 within which the associated locking rod 27 is slidably mounted, with the result that the springs 31 are continually urging the locking rods 27 to their extreme forward position, this forward position being indicated upon Fig. 2.

Means are associated with each of the locking rods 27 for moving them longitudinally inwards against the action of their associated 45 springs 31. A push rod 32 is reciprocably

mounted within the casing 6 adjacent each of the locking rods 27. The extent of the reciprocation of each of the push rods 32, is limited by a pin 35 or its equivalent, extending inwards from the exterior of the casing 6 into a slot 35' in the push rod 32, this slot 35' being so proportioned that the movement of the rod 32 is limited as desired. A coil spring 33 is under compression between the inner end of each of the push rods 32 and the inner end of the recess 34 within which that push rod is slidably mounted, urging the rod 32 to its outermost extreme of movement. Each of the push rods 32 carries a pawl 36 which is urged by a spring 37 to extend through a slot 38 in the casing 6 and engage a row of ratchet teeth 39 on the associated locking rod 27, the parts being so proportioned and arranged that when the push rod 32 is pressed inwards to the inner extreme of its movement, the pawl 36 will engage one of the teeth of the row 39 and move the associated locking rod 27 inwards a distance greater than the distance between two of the teeth 39, but less than the distance between three of the teeth 39.

Means are also provided for retaining the locking rods 27 against reversed sliding movement when the associated push rod returns to initial position. Each locking rod 27 is provided with a pawl 41 which is urged by a spring 42 to engage a ratchet tooth 43, a row of which is provided adjacent each of the locking rods 27, and all these rows of ratchet teeth 43 being formed upon a sleeve 44 which is mounted for rotary movement in the casing 6 and encircling a round portion 46 of the shank 11. A groove 47 is provided upon one side, and a smooth portion 48 is provided upon the other side of each of the rows 43 of ratchet teeth, these smooth portions 48 and grooves 47 extending parallel to their associated rows of teeth 43. Moreover, the sleeve 44 may be rotated to any one of three optional positions; and to facilitate this rotational adjustment of the sleeve 44, a plate 49 is rigidly attached to the flange 51 with which the sleeve 44 is provided, and a finger 52 extends radially outwards from the plate 49, beyond an enlarged head 53 of the shank 11. A projection 54 is formed upon the under side of the finger 52, to be removably received within any one of three depressions 56 in the front of the casing 6, to releasably retain the sleeve 44 in selected position, it being understood that the depressions 56 are so arranged that when the projection 54 is seated within the center one of the depressions 56, the rows 43 of ratchet teeth on the sleeve 44 will be in register with their respective pawls 41, when the projection 54 is seated within the right hand depression 56, the smooth portions 48 of the sleeve 44 will be in register with the pawls 41, and when the projection 54 is seated within the 55 60 65 70 75 80 85 90 95 100 105 110 115 120 125 130

left hand depression 56, the rows 43 of ratchet teeth will be in register with the grooves 47.

The plate 49 is securely attached to the flange 51 of the sleeve 44, as by a plurality of screws 55; and anti-friction bearings 57 are interposed between the head 53 and the plate 49, to eliminate friction between the shank 11 and the other parts of the lock when the shank 11 is turned.

A block 61, such as that shown in Fig. 7, is securable within each of the grooves 47, each of these blocks being provided with a plurality of teeth 62. It is to be observed however, that these teeth 62 are spaced a greater distance apart than the teeth 43 on the sleeve 44. As shown in Fig. 4, the teeth 62 are in alignment with alternate teeth 43 of the adjacent row of the sleeve 44. The blocks 61 are attachable to the sleeve 44 within their grooves 47, by means of screws 63 or their equivalent, and a plurality of screw holes 64 are formed in the bottom of each groove so that the block 61 may be positioned in any one of a plurality of locations. However, it is essential that each block be positioned so that one of the spaces 66 between two of the teeth 62, be in alignment with the associated pawl 41 when the locking rod 27 bearing that pawl, has been moved to bring its slot 28 into register with the flange 14. It is obvious then, that after all the locking rods 27 have been moved to unlocking position, a space 66 in each of the blocks 61, will be in register with the associated pawl 41, whereupon the finger 52 may be turned to the left to bring the grooves 47 of the sleeve 44, into register with the respective pawls 41. This will bring all the pawls 41 into spaces 66. If one of the push rods 32 is now pressed, inadvertently or otherwise, the combination will not be destroyed because the pawl 41 can not ride over the next tooth 62 of the block 61, the spacing between these teeth 61 being greater than the distance travelled by the associated locking rod 27 during each stroke. Fig. 8 shows a slightly modified form of block wherein the teeth 68 and 69 are separated a distance equal to that between three of the teeth 43.

The operation of the lock of the present invention is substantially as follows:

The operative parts of the lock are shown in initial or locked position upon Fig. 2. In order to unlock the mechanism, it is necessary to depress each of the push rods 32 a predetermined number of times, the number of depressions for each rod 32, being determined by the spacing of the associated notch 28 in the locking rod 27. As each push rod 32 is depressed, its pawl 36 engages one of the teeth 39 on the associated locking rod 27, and moves that locking rod inwards a distance determined by the length of the slot 35. Then, when the push rod 32 is released, its

spring 33 will return it to initial position, but the locking rod 27 is restrained against returning to initial position, by its pawl 41 coming into engagement with the after side of one of the teeth 43 on the sleeve 44, it being understood of course, that the finger 52 has first been moved to central position. When the push rod 32 is again depressed, the associated locking rod 27 will be moved inwards another step, and this operation of the push rod 32 is to be repeated that number of times which is necessary to bring the notch 28 into register with the flange 14. It is to be understood that the same process is to be carried out with each of the push rods 32, with the exception however, that the number of activations of each of the push rods to move their respective locking rods 27 to unlocking position, will not necessarily be the same, because of the fact that the notches 28 in the various locking rods 27, may be positioned differently in respect to the length of the rods 27. It is obvious therefore, that in order that the lock shall be released, the operator must have knowledge of the number of times each of the push rods 32 must be activated.

When all the push rods 32 have been depressed the proper number of times, the handle 29 may be turned so as to turn the shank 11 and operate the mechanism to which the lock is connected. If it be desired to so arrange the device that inadvertent destroying of the combination will be prevented, the finger 52 may be moved to bring its projection 54 into the left hand depression 56, which will dispose each of the pawls 41 within the space 66 of the associated block 61, as previously described. It is to be observed that if the blocks 61 were provided with but a single tooth 62, it would be possible for an unauthorized person to solve the combination and open the lock. This could be done by depressing all the push rods 32 a sufficient number of times to move all the locking rods 27 past unlocking position, and then moving the finger 52 to the left, bringing the grooves 47 into register with the pawls 41. Then the springs 31 would press all the locking rods 27 outwards until the pawls 41 engaged this single tooth 62, whereupon the locking rods 27 would all be in unlocked position. Therefore, by providing a plurality of teeth 62, at least one of which is nearer the inner end of the block 61 than that against which the associated pawl 41 is engaged when its locking rod 27 is in unlocked position, this method of solution of the combination is prevented. However, if there were but two of the teeth 62, it would still be possible for the lock to be solved relatively easily, by experimentation. For example, an unauthorized person could operate each of the push rods in succession, pressing the first push rod once, and then moving the finger 52 to the left. If this movement of the finger 52 resulted in a click,

caused by the locking rod 27 being pressed outwards by the spring 31, the person would know that the locking rod 27 had not been moved to unlocking position, whereupon he would depress the push rod 32 twice. Then, upon moving the finger 52 to the left, and hearing another click, he would depress the push rod 32 three times, and so on until he found the number of times that particular push rod 32 required being pressed to move its associated locking rod 27 to unlocking position. This process could be carried out with each of the push rods 32 until the entire combination has been solved. Therefore, by the provision of at least one tooth 62 between the forward end of the block 61 and that tooth 62 against which the associated pawl 41 engages when its locking rod 27 has been moved to unlocking position, this method of solving the combination, is prevented.

When it is desired to again set the lock, the finger 52 should be moved to right hand position, whereupon the smooth portions 48 will be brought into register with the pawls 41, and the springs 31 will push all the locking rods 27 to outermost position. Then, the lock can be released only by again properly manipulating the push rods 52.

If it be desired to change the combination, this may be done by substituting new locking rods 27, in which the notches 28 are differently disposed. When this is done, it is necessary to also move the associated blocks 61 so that they are positioned to be in register with the associated pawls 41 when the notch 28 is in register with the flange 14.

It is to be understood that the details of the invention as herein disclosed, are subject to alteration within the spirit or scope of the appended claims.

I claim:

1. A lock comprising a casing, a shank mounted for rotary movement therein, a flange carried by said shank and having a notch in the periphery thereof, a rod slidably mounted in said casing and extending through said notch to hold said flange and shank against rotary movement, said rod having a notch therein, means for sliding said rod in a predetermined number of successive steps to bring its notch into register with said flange and release the shank for rotary movement, and means operative to render said rod sliding means inoperative after the rod has been moved to releasing position.

2. A lock comprising a casing, a shank mounted for rotary movement therein, a flange carried by said shank and having a notch in the periphery thereof, a rod slidably mounted in said casing and extending through said notch to hold said flange and shank against rotary movement, said rod having a notch therein, means for sliding said rod in a predetermined number of successive

steps to bring its notch into register with said flange and release the shank for rotary movement, and means operative to render said rod sliding means inoperative.

3. A lock comprising a casing, a shank mounted for rotary movement therein, a flange carried by said shank and having a notch in the periphery thereof, a rod slidably mounted in said casing and extending through said notch to hold said flange and shank against rotary movement, said rod having a notch therein, means for sliding said rod in a predetermined number of successive steps to bring its notch into register with said flange and release the shank for rotary movement, means operative to render said rod sliding means inoperative after the rod has been moved to releasing position, and means for returning said rod to locking position.

4. A lock comprising a casing, a shank mounted for rotary movement therein, a flange carried by said shank and having a notch in the periphery thereof, a rod slidably mounted in said casing and extending through said notch to hold said flange and shank against rotary movement, said rod having a notch therein, means for sliding said rod in a predetermined number of successive steps to bring its notch into register with said flange and release the shank for rotary movement, means operative to render said rod sliding means inoperative after the rod has been moved to releasing position, resilient means urging said rod to locking position, and releasable means for holding said rods against the action of said resilient means.

5. A lock comprising a casing, a shank mounted for rotary movement therein, a flange carried by said shank and having a plurality of notches in the periphery thereof, a rod slidably mounted in said casing and extending through each of said notches to hold said flange and shank against rotary movement, each of said rods having a notch therein, means for sliding said rods in a predetermined number of successive steps to bring the notches in said rods into register with the flange and release the shank for rotary movement, means operative to render said rod sliding means inoperative, resilient means urging said rods to locking position, and releasable means for holding said rods against the action of said resilient means.

6. A lock comprising a casing, a shank mounted for rotary movement therein, a flange rigid with said shank and having a plurality of notches in its periphery, a locking rod slidably mounted in said casing and extending through each of said notches to hold the flange and shank against rotary movement, a push rod slidably mounted in said casing adjacent each of said locking rods, a ratchet and pawl mechanism inter-

posed between each of said push rods and its associated locking rod for sliding the locking rod a predetermined distance each time the push rod is activated, a sleeve mounted for rotary movement within the casing, and a ratchet and pawl mechanism interposed between said sleeve and each of said locking rods to hold the locking rod against reversed sliding movement when the associated push 10 rod returns to the beginning of its stroke.

7. A lock comprising a casing, a shank mounted for rotary movement therein, a flange rigid with said shank and having a plurality of notches in its periphery, a locking rod slidably mounted in said casing and extending through each of said notches to hold the flange and shank against rotary movement, a push rod slidably mounted in said casing adjacent each of said locking 15 rods, a ratchet and pawl mechanism interposed between each of said push rods and its associated locking rod for sliding the locking rod a predetermined distance each time the push rod is activated, a sleeve mounted for rotary movement within the casing, a ratchet and pawl mechanism interposed between each of said locking rods to hold the locking rod against reversed sliding movement when the associated push 20 rod returns to the beginning of its stroke, means for turning said sleeve to disconnect the ratchet and pawl mechanisms associated therewith, and resilient means for returning said locking rods to initial position after the 25 sleeve has been turned to disconnecting position.

8. A lock comprising a casing, a shank mounted for rotary movement therein, a flange rigid with said shank and having a plurality of notches in its periphery, a locking rod slidably mounted in said casing and extending through each of said notches to hold the flange and shank against rotary movement, resilient means urging said locking rods to locking position, a push rod slidably mounted in said casing adjacent each of said locking rods, a ratchet and pawl mechanism interposed between each of said push rods and its associated locking 30 rod for sliding the locking rod a predetermined distance each time the push rod is activated, a sleeve mounted for rotary movement within the casing, a row of ratchet teeth on said sleeve adjacent each of said locking rods, a pawl carried by each of said locking rods in position to engage a tooth of the associated row and hold the locking rod against reversed sliding movement as the associated push rod returns to initial position, said sleeve having a smooth area extending along one side of each of said rows of ratchet teeth, and means for turning said sleeve to bring said smooth areas into register with the associated pawls and release 35

the push rods for their return to initial position.

9. A lock comprising a casing, a shank mounted for rotary movement therein, a flange rigid with said shank and having a plurality of notches in its periphery, a locking rod slidably mounted in said casing and extending through each of said notches to hold the flange and shank against rotary movement, resilient means urging said locking rods to locking position, a push rod slidably mounted in said casing adjacent each of said locking rods, a ratchet and pawl mechanism interposed between each of said push rods and its associated locking rod for sliding the locking rod a predetermined distance each time the push rod is activated, a sleeve mounted for rotary movement within the casing, a row of ratchet teeth on said sleeve adjacent each of said locking rods, a pawl carried by each of said locking rods in position to engage a tooth of the associated row and hold the locking rod against reversed sliding movement as the associated push rod returns to initial position, said sleeve having a groove extending along one side of each of said rows of ratchet teeth, a block disposed within each of said grooves and comprising a pair of spaced shoulders in alignment with two non-adjacent teeth of the associated row, the 40

50

10. A lock comprising a casing, a shank mounted for rotary movement therein, a flange rigid with said shank and having a plurality of notches in its periphery, a locking rod slidably mounted in said casing and extending through each of said notches to hold the flange and shank against rotary movement, resilient means urging said locking rods to locking position, a push rod slidably mounted in said casing adjacent each of said locking rods, a ratchet and pawl mechanism interposed between each of said push rods and its associated locking rod for sliding the locking rod a predetermined distance each time the push rod is activated, a sleeve mounted for rotary movement within the casing, a row of ratchet teeth on said sleeve adjacent each of said locking rods, a pawl carried by each of said locking rods in position to engage a tooth of the associated row and hold the locking rod against reversed sliding movement as the associated push rod returns to initial position, said sleeve having a groove extending along one side and a smooth area extending along the other side of each of said rows of ratchet teeth, a block disposed within each of said grooves and comprising a pair of spaced shoulders in alignment with two non-adjacent teeth of the associated row, the 55

110

115

120

125

130

space between said shoulders being in alignment with the associated retaining pawl when the associated locking rod is in flange releasing position, and means for optionally turning said sleeve to bring said rows of teeth, said grooves, or said smooth areas into register with the associated pawls.

11. A lock comprising a casing, a shank mounted for rotary movement therein, a flange rigid with said shank and having a plurality of notches in its periphery, a locking rod slidably mounted in said casing and extending through each of said notches to hold the flange and shank against rotary movement, resilient means urging said locking rods to locking position, a push rod slidably mounted in said casing adjacent each of said locking rods, a ratchet and pawl mechanism interposed between each of said push rods and its associated locking rod for sliding the locking rod a predetermined distance each time the push rod is activated, a sleeve mounted for rotary movement within the casing, a row of ratchet teeth on said sleeve adjacent each of said locking rods, a pawl carried by each of said locking rods in position to engage a tooth of the associated row and hold the locking rod against reversed sliding movement as the associated push rod returns to initial position, said sleeve having a groove extending along one side of each of said rows of ratchet teeth, a block disposed within each of said grooves and comprising a pair of spaced shoulders in alignment with two non-adjacent teeth of the associated row, the space between said shoulders being in alignment with the associated retaining pawl when the associated locking rod is in flange releasing position, means for turning said sleeve to bring said grooves into register with said pawls, and means for varying the position of each of said blocks in respect to the associated row of ratchet teeth.

12. A lock comprising a casing, bolt-operating means therein, a plurality of locking rods slidably mounted in said casing in position to optionally release or hold said bolt-operating means inoperative, means for moving each of said rods in a predetermined number of steps into releasing position, a sleeve mounted for rotary movement within said casing, and a ratchet and pawl mechanism interposed between each of said rods and said sleeve to hold each rod against return movement between successive steps of said rod-moving means.

13. A lock comprising a casing, bolt-operating means therein, a plurality of locking rods slidably mounted in said casing in position to optionally release or hold said bolt-operating means inoperative, means for moving each of said rods in a predetermined number of steps into releasing position, a sleeve mounted for rotary movement within said casing, a ratchet and pawl mechanism inter-

posed between each of said rods and said sleeve to hold each rod against return movement between successive steps of said rod-moving means, means for turning said sleeve to disconnect said ratchet and pawl mechanisms, and resilient means for returning said locking rods to initial position after the sleeve has been turned to disconnecting position.

14. A lock comprising a casing, bolt-operating means therein, a plurality of locking rods slidably mounted in said casing in position to optionally release or hold said bolt-operating means inoperative, means for moving each of said rods in a predetermined number of steps into releasing position, a sleeve mounted for rotary movement within said casing, a row of ratchet teeth on said sleeve adjacent each of said rods, a pawl carried by each of said rods in position to engage a tooth of the associated row and hold the associated rod against return movement between successive steps of said rod-moving means, said sleeve having a groove extending along one side of each of said rows of ratchet teeth, a block disposed within each of said grooves and comprising a pair of spaced shoulders in alignment with two non-adjacent teeth of the associated row, the space between said shoulders being in alignment with the associated retaining pawl when the associated locking rod is in releasing position, and means for turning said sleeve to bring said grooves into register with said pawls.

15. A lock comprising a casing, bolt-operating means therein, a plurality of locking rods slidably mounted in said casing in position to optionally release or hold said bolt-operating means inoperative, means for moving each of said rods in a predetermined number of steps into releasing position, a sleeve mounted for rotary movement within said casing, a row of ratchet teeth on said sleeve adjacent each of said rods, a pawl carried by each of said rods in position to engage a tooth of the associated row and hold the associated rod against return movement between successive steps of said rod-moving means, said sleeve having a smooth area extending along one side of each of said rows of ratchet teeth, spring means urging each of said locking rods to locking position, and means for turning said sleeve to bring said smooth areas into register with said pawls.

In testimony whereof I have signed my name to this specification.

HANS WEISSENBOECK.
